UNITED STATES PATENT OFFICE.

LEWIS E. MORRISON, OF NEWARK, NEW JERSEY, ASSIGNOR TO HUMANA COMPANY, A CORPORATION OF NEW JERSEY.

PRINTING-MACHINE.

1,245,759.

Specification of Letters Patent.

Patented Nov. 6, 1917.

Application filed November 2, 1915. Serial No. 59,161.

To all whom it may concern:

Be it known that I, LEWIS E. MORRISON, a citizen of the United States, and resident of Newark, in the county of Essex and State of New Jersey, have invented certain new and useful Improvements in Printing-Machines, of which the following is a specification.

This invention relates to improvements in printing mechanisms and the object of the invention is to provide generally improved devices or mechanisms for job presses with particular reference to the separating and feeding operations thereof.

Aside from the general aim of the invention which is to provide improved means for carrying out the several said operations on a job printing press, it is the object of the invention to arrange and construct the various mechanisms in such a manner that they may be attached to existing types of job presses without requiring material alterations of the machines and with a view of making such job presses almost wholly automatic in their operations and whereby particularly the feeding mechanism is so arranged as to make it wholly safe for the operator to attend to the press in this respect.

Another object of the invention is to construct the various parts and combinations thereof in a simple, practical manner with a view of being able to transform a hand-fed and hand-delivery job press into an automatic machine at a relatively low cost.

Other objects of the invention will appear hereinafter.

Accordingly, my invention is embodied in mechanisms, parts and combinations thereof, arranged and combined as hereinafter set forth and as illustrated in the accompanying drawings in which

Figure 1 is a side elevation in outline of a job printing press equipped with automatic mechanisms, according to my invention.

Fig. 2 is a perspective view of the separating, feeding and delivery means.

Fig. 3 is a detail sectional view of the separator.

The invention is illustrated in connection with a well known type of job press, but I claim the use of the invention on other types of printing presses as well and where only the mechanical ability of one skilled in the art would be required for the purpose

of adapting this invention to a different machine.

Referring to the drawings the numeral 1 designates the frame of the press; 2 is the platen which oscillates on its pivot 3 in the frame in a well known manner by means not necessary to describe or illustrate in order to understand this invention. 4 is the power shaft which carries a pinion 5 for driving a large gear 6 from which the form member 7, pivoted at 8, is operated in the usual manner.

9 designates the feed board which may be a sheet of metal secured to supporting brackets 10; one on each side frame 1 of the press and attached thereto by bolts 11. Paper side guides 12 are adjustably mounted on the feed board by means of slotted members 13 and screws 14. The front edge of the paper 15 is squared against paper stops 16 secured to a rockshaft 17 which is operated from the usual and well known platen locking cam 18 by means of the arm 19, link 20 and roller arm 21, which latter is pivoted to the press at 22 and carries a roller 23 which runs upon the cam 18. By these means the paper stops are periodically lifted to permit the paper to pass out from under them.

The paper, which includes carboard, envelopes and all other stock adapted to be printed on a job press, is combed out as shown and placed between the guides 12 with the upper sheet projecting beyond the sheet underneath and having its front edge squared against the paper stops.

The paper is fed to the platen by means of a paper separating and feeding device which comprises the suction cup 24 adjustably carried by the hollow rod or tube 25 by means of a set screw 26. The rod 25 is secured in the free end of the feeder arm 27 which is pivoted at 28 to the lever 29. Suitable stops 127 and 129 are provided to prevent the arm 27 from falling down and to permit it to be moved upward into a position of rest in order to make the press ready. The arm 29 is pivoted at 30 on an auxiliary frame 31 and carries a cam roll 32 running in the cam 33. 34 denotes the pump which is connected by a flexible tube 35 to the tube 25 aforesaid and the suction cup 24. The latter has a hollow stem and a recessed foot 36 provided with a lining 37 of leather, rubber or similar material. 38 is a rubber-

rimmed wheel on the tube 25 and which forms a supporting and guiding means for the said tube and the suction cup 24 in that the said wheel runs on cams 39 and 40. Cam 39 is fixed to the feed board and cam 40 is secured to the platen 2. The pump is operated from the shaft 41 in the auxiliary frame 31, which may be secured to the press or to the floor in any suitable manner. The shaft 41 has a crank 42 which is adjustably connected at 43 to the piston rod 44 of the pump. The shaft 41 carries a gear 45 in mesh with the gear 6 aforesaid. The top sheet of paper is separated from the pile by having its front edge sucked up by the suction cup 24 during the suction stroke of the pump, the commencement of which is shown in Fig. 1, where the separator is about to pick up the top sheet as soon as the cam roll 32 gets on the low part of cam 33.

At this time the paper stops 16 are raised because their operating roll 23 is on the low part of the platen locking cam 18. As the press now opens, the cam 33 causes the lever 29 to move forward or to the left in Fig. 1 with the separator and the latter moves down upon the platen with the sheet and delivers it directly upon the platen. During its forward motion the separator is guided by its wheel 38 running on the fixed cam 39 and as the platen reaches full open position, the wheel 38 passes from the cam 39 onto the cam 40 on the platen as shown on Fig. 2. The separator has a fixed length of movement from the rear of the feed board to the rear of the platen, but the sheet may be released by the separator to deliver the sheet upon the platen in any predetermined position. To this end the pump casing is provided with a pin 134 and the piston 135 is provided with an aperture 136. A cover 137 is pivoted on the piston and is normally closed upon the aperture 136 by a spring 138 secured in any suitable manner. The cover has a tail 139. When the latter strikes the pin 134 on the suction stroke, the tail is depressed and the cover lifted to admit air through the aperture 136 to the connection 35 and the separator. By raising or lowering the pin 134, which is held frictionally in the pump casing, the point of release of the sheet from the separator may be adjusted. On the return stroke, the separator is first lifted as the cam 40 moves down with the platen and from this cam the wheel 38 passes back to the fixed cam 39 and to the paper.

When the top sheet has left the pile the paper stops 16 move down again as now the roll 23 will run on the high part of the platen locking cam. During the movement of the sheet from the feed board to the platen, the corners of the sheet are prevented from being blown upward by the clips 48 on

the rod 25 as is apparent from Fig. 2. 49 is a paper holding device comprising a leaf 50 adjustable lengthwise at 51 and pivoted at 52 to a support 53. 54 is a spring which forces the leaf down on the rear edge of the paper, so that as the top sheet is pulled off the leaf 50 serves to retain the sheet next to the top one and prevent two sheets from being picked up at one time. The object of the paper holding device 49 is to permit the operator to leave the press momentarily to get more paper for instance. Normally the operator is supposed to keep his hands on the paper and see to it that only one sheet at a time is fed to the platen.

After the paper has been printed it is removed from the platen by the delivery mechanism not shown and in order to guide the paper unto the platen and permit the delivery mechanism to take the printed sheet 85 away from the platen before the fresh sheet covers it up there is provided a feed table which comprises paper guides 55, 55, two of which have side guides 56, 56, provided with top guides 57, 57 for preventing the sheet 90 from being blown upward. The top guides are fastened on the side guides 56 like clips and may be adjusted thereon. All the guides are mounted on a flat bar 58 pivoted to the brackets 10 at 59 and the guides may be moved along said bar for adjustment according to the width of the sheet. 60 is a supporting finger secured to the bar 58 and which rests by the weight of the feed table on a cam 61 secured to the platen as is clearly shown. In Fig. 1 the paper feed table is lifted by said cam 61 and as the platen moves up the feed table is lowered to the position shown in Fig. 2 to guide the paper onto the platen. The feed table is 105 adapted to be swung upward on its pivots 59 in order to make the press ready.

The operation of the devices contained in this invention will be clear from the foregoing. It is also clear that hardly any 110 change is made in the press itself but that the entire feeding and delivery apparatus may be built as an attachment to the press and that by properly mounting the other auxiliary parts, a hand operated press may 115 be quickly transformed in an almost wholly automatic machine.

The several parts and details may be varied in their construction from the specific forms shown and described, and I claim all 120 such changes and modifications in my invention as properly come within the principle thereof and the scope of the appended claims.

I claim:—

1. The combination with a platen and a feed board supporting the sheets to be printed, a sheet separating device, means for operating the same to separate the top sheet and deliver it to the platen, a fixed cam on 125

- said feed board, a cam secured to the platen and means on said separating device adapted to operate on said cams for supporting the said device during its movements between the feed board and the platen.
2. The combination with a platen and a feed board supporting the sheets to be printed, a sheet separating device, means for operating the latter to separate the top sheet and deliver it on the platen, and means for adjusting the operation of the said separating device to cause the same to deliver the sheet on the platen in a predetermined position.
- 10 3. The combination with a platen and a feed board supporting the sheets to be printed, a sheet separating device, means for operating the latter to separate the top sheet, means for adjusting the operation of the said separating device to cause it to deliver a sheet in a predetermined position on the platen and means for supporting said device during its movements between the feed board and platen.
- 20 4. The combination with a movable platen and a feed board supporting the sheets to be printed, a suction sheet separating device, means for operating the same to separate the top sheet and deliver it on the platen and means for adjusting the release of the suction in said device to cause the sheet to be delivered in a predetermined position on said platen.
- 30 5. The combination with a movable platen and a fixed feed board supporting the sheets to be printed, a sheet separating device, means for operating the same to separate the top sheet and deliver it to the platen, a cam secured to said feed board, a second cam secured to said movable platen and means on said separating device adapted to operate on said cams to support said device during the operations thereof.
- 40 6. The combination with a movable platen and a fixed feed board supporting the sheets to be printed, a sheet separating device, means for operating the same to separate the top sheet and deliver it to the platen, a cam secured to said feed board, a second cam secured to said movable platen and means on said separating device adapted to support said device during the operations thereof.
- 45 and a fixed feed board supporting the sheets to be printed, a sheet separating device, means for operating the same to separate the top sheet and deliver it to the platen, a cam secured to said feed board, a second cam secured to said movable platen and a roller on said separating device adapted to operate on said cams to support said device during the operations thereof.
- 50 7. The combination with a platen and a feed board, a lever, an arm pivoted at its one end on said lever, a suction member carried by said arm, means for actuating said lever to operate the said suction device to deliver a sheet from the feed board to the platen and means secured to the free end of said arm for supporting the suction device during its said movements.
- 55 8. The combination with a movable platen and a feed board, a lever, an arm pivoted at its one end to said lever, a suction member carried by said arm, a cam on said feed board, a second cam on said movable platen, means for actuating said lever to operate the suction device to deliver a sheet on the platen from the said feed board and a roller secured to said arm and adapted to operate on the said two cams for supporting the free end of said arm during the operations thereof.
- 60 9. The combination with a platen and a feed board supporting the sheets to be printed, means for feeding sheets to said platen and placing the sheets thereon in predetermined variable positions comprising a sheet separating device movable from a position at the front edge of said feed board to the front edge of said platen and means for effecting such movement of the said separating means.
- 65 Signed at New York in the county of New York and State of New York this 29th day of October A. D. 1915.
